REEL

Fred J. Samerdyke, Cleveland, Ohio, assignor to
 Industrial Rayon Corporation, Cleveland, Ohio,
 a corporation of Delaware

Application April 29, 1936, Serial No. 76,995

13 Claims. (Cl. 242—53)

This invention concerns a novel form of winding reel.

More particularly, the invention relates to a winding reel comprising a plurality of sets of longitudinally extending interdigitating bar members, usually, but not necessarily, two in number, each of which is substantially circular in cross section. In winding reels of the kind to which the invention relates, the respective sets of bar members are mounted in such relation to each other that some of the bar members of each set project beyond the generally cylindrical periphery defined by the bar members of the other set. Inasmuch as each set of bar members is rotatable about its own axis, the individual bar members projecting at any given time are necessarily constantly changing, resulting in the course of any given revolution of the reel as a whole in the transfer from one set of bar members to the other of the material, such, for example, as thread or the like, wound on the reel. The bar members of at least one set are adapted to move lengthwise of the reel while carrying the thread or the like, whereby the thread or the like is caused to advance lengthwise of the reel, during rotation thereof, in a plurality of spaced, generally helical turns.

The present invention provides a reel of the above type of cantilever construction, the term "cantilever" being intended to express the thought that the reel is supported and driven from one end only. The other end of the reel may thus be left wholly unobstructed permitting ready access to the reel for manipulation of the material wound thereon, inspection, adjustment, etc. Reels of the above type may be adapted to store a relatively long length of thread or the like in a small space in a plurality of spaced generally helical turns and may therefore be conveniently employed in the continuous processing of thread or the like. Cantilever thread storage reels, such as that provided by the present invention, may be employed to particular advantage for such purposes, since they lend themselves to disposition in arrangements in which, by virtue of their open ended construction, threading up and other manipulation of the thread or the like stored on the reels, inspection, replacement, repair, etc., are very greatly facilitated.

The cantilever reel illustrated as embodying the invention is of a type comprising a rigid, generally cylindrical set of longitudinally extending bar members having alternating therewith the bar members of a non-rigid generally cylindrical set of otherwise similar bar members. The bar

member of the non-rigid set are connected to at least one, and preferably two or more, actuating members rotatably mounted about axes laterally offset from and inclined to the axis of the rigid set of bar members. Rotation of the reel causes thread or the like to wind on the reel, the offset relationship of the axes of the two sets of bar members causing the thread or the like to be transferred from one set of bar members to the other. The longitudinal reciprocating motion imparted to the bar members of the non-rigid set by rotation of the actuating member or members about inclined axes causes the thread or the like wound on the reel to advance lengthwise of the reel in a plurality of spaced, generally helical turns.

One form of reel embodying the invention is illustrated in Figure 1, which shows a longitudinal sectional elevation of the reel, the section being along line 1—1 of Figure 2. Figure 2 is an end elevation of the reel from line 2—2 of Figure 1. Figure 3 is a plan of the reel from line 3—3 of Figure 2, parts being broken away more clearly to show the construction of the reel. Figure 4 is a detail on an enlarged scale of one form of means which may be employed for mounting the bar members of the non-rigid set. Figure 5 is a sectional elevation from line 5—5 of Figure 4. Figure 6 is a sectional elevation, from line 6—6 of Figure 7, showing modified means for mounting the actuating members on the supporting frame of the reel. Figure 7 is a sectional elevation of the modification of Figure 6 from line 7—7 of Figure 6. Figure 8 is a sectional elevation from line 8—8 of Figure 7.

In the drawings, like reference numerals refer to like parts throughout.

The reel shown in the drawings comprises a rigid, generally cylindrical reel member 1 and a non-rigid, generally cylindrical reel member 2. Rigid reel member 1 has a periphery formed of a plurality of spaced, longitudinally extending bar members 3 with which alternate the bar members 4 forming the periphery of non-rigid reel member 2. While reel member 1 may take any of various forms and may be mounted and driven in various ways, in the embodiment shown it comprises a rigid, cage-like member 5 which embodies the bar members 3, supported at one end thereof by spider 6 and provided at the other end with an external annular ring 7. The latter may serve to reinforce the bar members 3 and may constitute a guide for the thread or the like. The cage-like member 5 is supported at the operating end of the reel by an angular sup-

porting member 8 fixed to the annular ring 7, as by cap-screws 9. Annular supporting member 8 is journalled on the frame member 11 on which the reel is mounted. The illustrated reel is driven by a shaft 12 journalled in frame member 11 concentrically with annular supporting member 8. Spider 6 of reel member 1 is mounted on and fixed for rotation with the shaft 12 by key 13 and cap-bolt 14 threaded into the end of shaft 12.

The non-rigid reel member 2 comprises a set of bar members 4 non-rigidly mounted on two actuating members 15 and 16, preferably of disk-like form, rotatably supported about axes offset from and slightly inclined to the axis of the shaft 12 and consequently to the axis of rigid reel member 1. The axes of actuating members 15 and 16 are preferably disposed as illustrated in parallel relation to each other. In the embodiment shown, actuating members 15 and 16 are rotatably mounted on frame member 11, suitable means being provided to locate them in the desired position. In the means illustrated, ring-nut 17, threaded onto frame member 11 and locked into position by set-screw 18, and bearing washer 19 are provided to retain actuating member 15 against a suitable shoulder 20 on frame member 11. If desired, suitable means such as oil grooves 21 may be provided to lubricate shaft 12 and the bearing surfaces on which actuating members 15 and 16 are journalled.

Bar members 4 of non-rigid member 2 are non-rigidly mounted on actuating members 15 and 16 by means providing movement in a variety of different directions such, for example, as the means illustrated in Figures 4 and 5. In the mounting means illustrated, the corresponding bar member 4 is provided with a slot 22 into which projects the end of pin 23 pivotally mounted therein by a pivot pin 24. If desired, the end of pin 23 may be flattened as shown to provide guiding surfaces to bear against the walls of slot 22 in the bar member 4. The pin 23 is journalled in a suitable sleeve nut 25 threaded into the corresponding actuating member, in Figures 4 and 5 bearing reference numeral 15. By means of sleeve nut 25 and head 26 on pin 23, pin 23 is maintained in the desired position with relation to actuating member 15, being prevented from movement other than rotary movement about the axis of pin 23, while the bar member 4 is allowed a pivotal movement about pivot pin 24.

By the mounting means above described, each bar member 4 is permitted substantially universal motion with respect to actuating members 15 and 16 without, however, being permitted to twist about an axis extending longitudinally of the bar members. Furthermore, the mounting means illustrated provides ease of assembly of the non-rigid member, since pin 23 may first be passed through sleeve nut 25 after which the corresponding bar member 4 may be fastened to pin 23 by pivot pin 24, the bar members 4 being then fastened in the desired position on actuating members 15 and 16 by simply screwing the sleeve nuts 25 into threaded holes provided on the periphery of the actuating members.

The reel illustrated is particularly adapted for employment in the continuous processing of thread or the like, particularly in the wet processing of thread or the like, wherein processing liquid is applied to the thread or the like by showering the liquid on the thread or the like from distributors disposed thereabove. Since such processing liquids, as well as other processing media which

may be used, may be corrosive in character, it is desirable that the reel be constructed of materials and/or in a manner resistant to chemical action. This end is accomplished in the illustrated reel, in which parts such as cage-like member 5, annular supporting member 8, cap-screws 9, bar members 4, and rotatable actuating members 15 and 16 may be formed of suitable material, such as synthetic resin, resistant to the action of processing media; while flexible sealing means, such as the bellows-like members 29, 30 and 31 may be provided as indicated to enclose the interior portions of the reel, including the bearing surfaces, etc.

The bellows-like members may be mounted in any suitable manner, such as that shown. Member 29 is conveniently mounted on the hubs of spider 6 and actuating member 15. Member 30 is similarly mounted on the hubs of actuating members 15 and 16. Member 31 has one end thereof mounted on the hub of actuating member 16 and the other end clamped between cage member 5 and annular supporting member 8. The sealing means, besides protecting parts which might be damaged by processing medium, also prevent the escape from the interior of the reel of lubricants which might otherwise soil thread or the like wound on the reel. Furthermore, in the illustrated embodiment, the bellows-like sealing member 30 extending between actuating members 15 and 16 may also serve to urge actuating member 16 against the locating shoulder formed on frame member 11, thus aiding bar members 4 in maintaining actuating member 16 in the correct position on frame member 11. The mounting means by which the bars 4 are connected to the actuating members 15 and 16 may obviously be made of metallic or non-metallic materials resistant to the action of the particular processing media employed.

In operation of the reel, rigid reel member 1 is rotated by shaft 12. Contact of the bar members 3 of rigid reel member 1 with the bar members 4 of non-rigid reel member 2 causes the latter reel member to rotate therewith. As shown in Figure 2, lateral displacement with respect to the axis of rigid reel member 1 of the axes on which actuating members 15 and 16 are mounted causes bar members 4 of non-rigid reel member 2 to project outward beyond bar members 3 of rigid reel member 1 during part of the complete revolution of the reel. Bar members 3 of rigid reel member 1 likewise project outward beyond those of non-rigid reel member 2 during the other part of the revolution. Thread or the like wound on the reel is thus transferred during the rotation of the reel from the bar members of one reel member to the bar members of the other reel member.

The mounting of the actuating members 15 and 16 about inclined axes causes bar members 4 mounted on actuating members 15 and 16 to be reciprocated lengthwise of the reel, the direction of offset and direction of inclination of these axes being so related that when said bar members 4 of non-rigid reel member 2 are projected beyond the bar members 3 of reel member 1 they are moved lengthwise of the reel in one direction, while when they are withdrawn within the generally cylindrical periphery defined by the bar members 3 of reel member 1, they are moved lengthwise of the reel in the opposite direction. The lengthwise movement of the bar members 4 of non-rigid reel member 2 produces bodily advance of the thread or the like during that por-

tion of the revolution of the reel during which these bar members support the thread or the like.

The thread advancing action of the reel of the present invention is generally similar to that of the reel shown in United States Patent No. 1,983,221 to William H. Furness. It will be understood that the thread or the like will move, for a given direction of rotation of the reel and for a given direction of lateral displacement of the axes of actuating members 15 and 16, in a direction along the reel determined by the direction of inclination of the axes of said actuating members 15 and 16 with respect to the axis of rigid reel member 1. Further, as the amount of inclination of these axes is modified, it is obvious that the pitch or lead of the generally helical turns of thread or the like is proportionately modified.

In the illustrated embodiment of the invention, for the direction of rotation indicated by the arrow in Figure 2 the thread or the like will advance along the reel from right to left as seen in Figures 1 and 3. This direction of advance; i. e., from the supported end of the reel to the unsupported end, constitutes the preferred direction of advance in cantilever reels; but it is, of course, obvious that by suitable modification of the construction of the reel the thread or the like could be caused to advance in the opposite direction. The net effect of the operation of the reel is to cause the thread or the like to be wound turn after turn about the reel in substantially helical form, the succession of turns meanwhile advancing bodily lengthwise of the reel. In this manner thread or the like led to the reel may be stored thereon in the form of a large number of closely spaced turns, as many as several hundred, depending upon the length of the reel.

The reel illustrated, besides having the advantages of cantilever construction has also the advantage of being readily assembled and disassembled. For instance, by removal of cap-bolt 14 and cap-screws 9, rigid reel member 1 may be disassembled and cage-member 5 removed, after which, by removal of the ring-nut 17, the non-rigid member 2 and annular supporting member 8 may be readily slid off the frame member 11. In the assembly of the reel, the parts of non-rigid member 2 can be assembled separately and the remainder of the reel assembled in the order opposite to that above indicated.

As shown in Figures 6 to 8, inclusive, actuating members 15 and 16, indicated by broken lines, may be mounted on a sleeve member 32 mounted on the frame member 11a of the reel, being held in the desired position thereon by set-screw 33. The frame member 11a, as shown in Figure 7, may be provided with a cylindrical exterior on which is mounted sleeve member 32, the axis of which is offset from but parallel to the axis of the bore for the drive shaft 12. The sleeve member 32 may therefore be formed with external surfaces which are substantially concentric, except for the inclined cylindrical bearing surfaces 34, 35 on which are rotatably mounted actuating members 15 and 16. It may be desirable to mount actuating members 15 and 16 on sleeve member 32 as shown in this embodiment, since the inclined bearing surfaces 34, 35 for actuating members 15 and 16 may be readily machined on said sleeve member 32, which may be more easily held in the machining apparatus than the frame member 11. Furthermore, it is obvious that by rotating the sleeve member 32 on the external cylindrical surface of the frame member 11a,

the offset and inclined relationship of the various axes is varied and thus the amount of pitch or lead of the helical turns of thread on the reel correspondingly varied.

It is apparent that under suitable circumstances only one actuating member need be provided to reciprocate the bar members of a non-rigid member, the bar members being supported by suitable means. Furthermore, it may be possible to have both sets of bar members of the reel of a non-rigid construction in which the bar members of each set are reciprocated lengthwise of the reel by one or more actuating members similar to actuating members 15 and 16 the offset and inclined relation of the axes of rotating parts of the respective reel members being arranged to provide a lengthwise movement of the bar members of each set in the desired direction when said bar members are supporting the thread or the like wound on the reel. It is to be understood that the above described reel is but an illustrative embodiment of the invention and that various other embodiments may be devised and various modifications besides those above indicated may be made in the illustrated embodiment without in any way departing from the spirit of the invention.

It is intended that the patent shall cover, by suitable expression in the appended claims, whatever features of patentable novelty reside in the invention.

What is claimed is:

1. A cantilever reel comprising a shaft having an unsupported end; a first reel member mounted about and adapted to be rotated by said shaft, said reel member having a periphery of substantially circular cross section comprising a plurality of bar members extending longitudinally of the reel; a frame member surrounding said shaft for at least a portion of its length and having an unsupported end extending in the same direction as that of said shaft; a second reel member supported by said frame member about an axis offset from the axis of revolution of said first reel member, said second reel member having a periphery of substantially circular cross section comprising bar members alternating with those of said first reel member; and means associated with said frame member for moving the bar members of said second reel member lengthwise thereof as said reel rotates.

2. A cantilever reel comprising a shaft having an unsupported end; a first reel member mounted about and adapted to be rotated by said shaft, said reel member having a periphery of substantially circular cross section comprising a plurality of bar members extending longitudinally of the reel; a frame member surrounding said shaft for at least a portion of its length and having an unsupported end extending in the same direction as that of said shaft; a second reel member supported by said frame member about an axis offset from the axis of revolution of said first reel member, said second reel member having a periphery of substantially circular cross section comprising bar members alternating with those of said first reel member; and means for moving the bar members of said second reel member lengthwise thereof as it rotates comprising an actuating member rotatably mounted on said frame member about an axis inclined to the axis of rotation of said first reel member, said actuating member being connected to the bar members of said second reel member.

3. A cantilever reel comprising a shaft having

- an unsupported end; a first reel member mounted about and adapted to be rotated by said shaft, said reel member having a periphery of substantially circular cross section comprising a plurality of bar members extending longitudinally of the reel; a frame member surrounding said shaft for at least a portion of its length and having an unsupported end extending in the same direction as that of the shaft; and a second reel member having a periphery of substantially circular cross section comprising bar members alternating with those of said first reel member, the bar members of said second reel member being non-rigidly connected to a pair of spaced, parallel members each of which is rotatably mounted on said frame member about an axis which is offset from and inclined to the axis of rotation of said first reel member.
4. A cantilever reel comprising a frame member supported from one end only; a rigid set of spaced, longitudinally extending bar members, which set is substantially circular in cross section, mounted for rotation about said frame member; a pair of spaced, parallel supporting members rotatably mounted on said frame member about independent axes which are offset from and inclined to the axis of rotation of said set of longitudinally extending bar members; a non-rigid set of spaced, longitudinally extending bar members, which set is substantially circular in cross section, non-rigidly connected to said pair of spaced, parallel supporting members, the bar members of said non-rigid set alternating with the bar members of said rigid set to define a reel structure one end of which is entirely unobstructed.
5. A cantilever reel comprising a frame member supported from one end only; a first set of spaced, longitudinally extending bar members, which set is substantially circular in cross section, mounted for rotation about said frame member; a pair of spaced, parallel supporting members rotatably mounted on said frame member about independent axes which are offset from and inclined to the axis of rotation of said first set of longitudinally extending bar members; and a second set of spaced, longitudinal extending bar members, which set is substantially circular in cross section, non-rigidly connected to said pair of spaced, parallel supporting members, the bar members of said second set alternating with the bar members of said first set to define a reel structure one end of which is entirely unobstructed.
6. A cantilever reel comprising a frame member supported from one end only; a first set of spaced, longitudinally extending bar members mounted for rotation about said frame member, said set being substantially circular in cross section; a second set of spaced, longitudinally extending bar members alternately disposed with the bar members of said first set, said set being substantially circular in cross section; and means associated with said frame member for projecting the bar members of said second set beyond the bar members of said first set and reciprocating the bar members of said second set lengthwise thereof during rotation of the reel, one end of the structure defined by said sets of bar members being entirely unobstructed.
7. A cantilever reel comprising a frame member supported from one end only; a first set of spaced, longitudinally extending bar members mounted for rotation about said frame member, said set being substantially circular in cross

section; a second set of spaced, longitudinally extending bar members alternately disposed with the bar members of said first set, said set being substantially circular in cross section; and means for rotatably supporting said second set of bar members from said frame members about an axis offset from the axis of rotation of said first set and reciprocating the bar members of said second set lengthwise thereof during rotation of the reel, one end of the structure defined by said sets of bar members being entirely unobstructed.

8. A cantilever reel comprising a frame member supported from one end only; a rigid set of spaced, longitudinally extending bar members surrounding said frame member, said set being substantially circular in cross section; two spaced members rotatably supporting said rigid set of longitudinally extending bar members; two spaced, parallel supporting members rotatably mounted on said frame member about independent axes which are offset from and inclined to the axis of rotation of said rigid set of bar members, said spaced, parallel supporting members being disposed between the members supporting said rigid set of longitudinally extending bar members; and, non-rigidly connected to said spaced, parallel supporting members, a non-rigid set of spaced, longitudinally extending bar members, alternating with the bar members of said rigid set, said set being substantially circular in cross section.

9. A cantilever reel comprising a frame member supported from one end only; a projecting shaft journaled in said frame member having its free end in proximity to the free end of said frame member; two interleaved sets of spaced, longitudinally extending bar members surrounding said frame member and supported therefrom, each of said sets being substantially circular in cross section; means for reciprocating the bar members of at least one of said sets lengthwise thereof during rotation of the reel; and means for rotating said sets of longitudinally extending bar members from the free end of said shaft.

10. A cantilever reel comprising a longitudinally extending frame member and, surrounding and supported from said frame member, two interleaved sets of longitudinally extending bar members, each of said sets of bar members being substantially circular in cross section, the bar members of at least one of said sets being non-rigidly connected to a rotatable member mounted about an axis inclined to the axis of the reel, and one end of the structure defined by said sets of bar members being unobstructed by supporting means for said sets of bar members.

11. A cantilever reel comprising a stationary, longitudinally projecting frame member which is supported at one end only thereof and which extends throughout the major portion of the length of the reel; two interleaved sets of spaced, longitudinally extending bar members, surrounding and rotatably supported from said frame member, each of said sets being substantially circular in cross section; and means associated with said frame member for causing the bar members of said sets to cooperate to advance lengthwise thereof material wound about said sets, one end of the structure defined by said sets of bar members being unobstructed by supporting means for said sets of bar members.

12. A cantilever reel comprising a stationary, longitudinally projecting frame member which is supported at one end only thereof and which extends throughout the major portion of the

length of the reel; two interleaved sets of spaced, longitudinally extending bar members surrounding said frame member, each of said sets being substantially circular in cross section; and means 5 leaving unobstructed one end of the structure defined by said sets of bar members rotatably supporting each of said sets of bar members from said frame member at points spaced longitudinally of the reel, said supporting means operating to cause the bar members of said sets to 10 cooperate to advance lengthwise thereof material wound about said sets of bar members.

13. A rigid reel member constituting one element of a cantilever thread-advancing reel comprising a set of spaced, parallel, longitudinally 15

extending bar members, said set being substantially circular in cross section; a reinforcing member substantially closing the end of said set of bar members rigidly fixed to the bar members of said set at one end thereof, the external diameter of said reinforcing member being no greater than the diameter at said end of the periphery of said set; and an annular member rigidly fixed to said bar members at the other end of said set, the internal diameter of said annular member 10 being at least as great as the diameter at said end of the periphery defined by the bar members of said set.

FRED J. SAMERDYKE. 15

CERTIFICATE OF CORRECTION.

Patent No. 2,181,916.

December 5, 1939.

FRED J. SAMERDYKE.

It is hereby certified that error appears in the printed specification of the above numbered patent requiring correction as follows: Page 1, second column, line 1, for the word "member" read members; line 55, for "angular" read annular; page 3, second column, line 14, after the reference numeral "16" insert a comma; page 4, first column, line 27, claim 4, after "said" insert rigid; same page, second column, line 6, claim 7, for "frame members" read frame member; and that the said Letters Patent should be read with this correction therein that the same may conform to the record of the case in the Patent Office.

Signed and sealed this 30th day of January, A. D. 1940.

(Seal)

Henry Van Arsdale,
Acting Commissioner of Patents.
